UNITED STATES PATENT OFFICE.

GEORGE H. JAQUES, OF CASPER, WYOMING.

CASING HEAD.

Application filed February 1, 1927. Serial No. 165,127.

The invention relates to a novel form of casing head for oil wells and the like, provided with a set of slips to land or support an inside string of casing or tubing and a second set of slips to anchor the inside string of casing or tubing, with packing interposed between the respective sets of slips and held in position by the anchoring slips, whereby the packing may be applied, removed or adjusted without effecting the relation of the supporting and landing slips and the inner string of casing or tubing, the particular coordination of the casing head and the slips preventing the accidental movement of the inner string of casing or tubing in either direction with respect to the casing to which the head is applied. The invention is illustrated in the accompanying drawings, in which:—

20 Fig. 1 is a sectional elevation of the head as applied to the outer casing and the inner casing or tubing.

Fig. 2 is a vertical sectional elevation of the supporting or landing slips.

25 Fig. 3 is a plan view thereof.

Fig. 4 is a sectional elevation of the anchoring slips.

Fig. 5 is a plan view thereof.

Referring to the drawings, 1 indicates the 30 main or body portion of the tubular head, the lower end of which is provided with internal screw threads 2 to engage the threaded end of the outer casing C. The interior of the tubular body portion 1 is provided 35 with an intermediate downwardly tapered bore 5 which constitutes a seat for the landing or supporting slips and above the tapered bore is a cylindrical bore section 3 having an annular shoulder 4 at its bottom, 40 which serves as a seat for the lower packing ring.

45 Removably engaging the downwardly tapering bore section 5 are the supporting or anchoring slips 10, which are arcuate in cross section and have their inner faces provided with upwardly inclined teeth or serrations 11 and their outer peripheral faces beveled or inclined to engage the inclined wall of the tapered bore section 5. As indicated in Fig. 1, the serrated inner faces of the slips surround and engage the inner string of casing or tubing T and prevent any downward movement of the latter.

50 Mounted in the cylindrical upper bore section 3 is a suitable packing comprising overlapping compressible gaskets 15 held be-

tween lower and upper split packing rings 16, 16, the former of which rests upon the annular shoulder 4.

Engaging the upper end of the cylindrical portion of the bore and the packing therein are anchoring slips 18, which are arcuate in cross section and have their interior surfaces provided with a series of annular downwardly extending teeth or serrations 19 and 60 their outer peripheral faces provided with an upward taper, so that the slips, when assembled, constitute a vertical split frustum of a cone, which surrounds the inner string of casing or tubing T, as indicated in Fig. 1, 70 with the lower end of the slip sections engaging the packing.

Secured in the upper end of the tubular member 1 is a series of studs or bolts 23 having adjusting nuts 24 on their outer ends, 75 said bolts passing through holes 22 in an anchoring ring 20, the inner periphery of which ring is provided with a downwardly flaring or tapering surface 21 cooperating with the upwardly tapering surfaces of the 80 slips 18.

The various parts are assembled and adjusted as illustrated in Fig. 1; that is to say, the casing head 1 is engaged with the upper end of the outer casing C and the 85 landing or supporting slips 10 are driven home in the tapered section 5 of the bore, so that the teeth or serrations on the inner faces of the slips bite into the surface of the inner casing or tubing T and rigidly support the 90 latter against downward movement. The packing is then applied in the upper cylindrical bore section 3, as shown, and the upper or anchoring slips placed in position above the packing, after which the anchor 95 ring 20 is threaded over the bolts 23. As the nuts 24 are set up on the bolts 23, the anchoring slips are tapped down evenly with a hammer until the packing 15 is sufficiently compressed to produce a fluid-tight 100 joint between the casing head and the inner string of casing or tubing. This precaution is necessary in order to prevent the anchoring slips from gripping the inner string before the packing is sufficiently compressed 105 to effect a tight joint.

As thus constructed and applied, it will be seen that the new casing head not only serves to support the weight of the anchored string of casing or tubing within the outer casing and prevents the well pressure from raising the inner string, but inasmuch as

the packing is held in position and properly compressed by the upper anchoring slips, it will be apparent that both the packing and the upper anchoring slips may be applied and adjusted without moving or handling the inner string of casing or tubing, as the latter is supported in the casing head 1 by means of the lower or landing slips 10. This construction also permits of the head 10 being used as a spider for handling the inner string of casing or tubing T, as the latter may be placed and adjusted within the outer casing by removing the upper anchoring slips and the packing, which latter are 15 reapplied after the inner casing or tubing has been properly landed or positioned.

What I claim is:

1. A casing head comprising a tubular member adapted to be secured to the well 20 casing and provided with a downwardly tapering bore, arcuate slips having serrated inner faces and tapered outer peripheral faces engaging the tapered bore, packing in the bore above the slips, arcuate anchoring 25 slips above the packing having serrated faces and upwardly tapered peripheral outer faces, an anchor ring having a tapered opening engaging the peripheral faces of said anchoring slips, and means for adjustably connecting said ring to the upper end of the 30 tubular member.

2. A casing head comprising a tubular member adapted to be secured to the well 35 casing and provided with a downwardly tapering bore, arcuate slips having serrated inner faces and tapered outer peripheral faces engaging the tapered bore, packing in the bore above the slips, arcuate anchoring 40 slips above the packing having serrated faces and upwardly tapered peripheral

outer faces, an anchor ring having a tapered opening engaging the peripheral faces of said anchoring slips, and bolts engaging the upper end of the tubular member for adjusting the anchor ring.

3. A casing head comprising a tubular member adapted to be secured to the upper end of a well casing and having a cylindrical upper bore section and a downwardly tapering lower bore section, arcuate landing slips having serrated inner faces and tapered outer peripheral faces engaging the tapered bore, packing in the cylindrical bore section, arcuate anchoring slips above the packing having serrated inner faces and upwardly tapered peripheral outer faces, an anchor ring having a tapered opening engaging the peripheral faces of said anchoring slips, and means for adjustably connecting said ring to the upper end of the 60 tubular member.

4. A casing head comprising a tubular member adapted to be secured to the upper end of a well casing and having a cylindrical upper bore section and a downwardly 65 tapering lower bore section, arcuate landing slips having serrated inner faces and tapered outer peripheral faces engaging the tapered bore, packing in the cylindrical bore section, arcuate anchoring slips above the 70 packing having serrated inner faces and upwardly tapered peripheral outer faces, an anchor ring having a tapered opening engaging the peripheral faces of said anchoring slips, and bolts engaging the upper end 75 of the tubular member for adjusting the anchor ring.

In testimony whereof I affix my signature.

GEORGE H. JAQUES.
